UNITED STATES PATENT OFFICE.

ANDREW COCHRAN, OF TRENTON, NEW JERSEY.

DESIGN FOR A FLUSH-TANK.

45,085.

Specification for Design.

Patented Dec. 30, 1913.

Application filed September 26, 1913. Serial No. 792,063. Term of patent 14 years.

To all whom it may concern:

Be it known that I, ANDREW COCHRAN, a citizen of the United States, and a resident of Trenton, Mercer county, New Jersey, have invented a new, original, and ornamental Design for Flush-Tanks, of which the following is a specification, reference being had to the accompanying drawing, in which—

Figure 1, is a front elevation of the flush tank; Fig. 2, is a perspective view looking

toward the left side of the tank; Fig. 3, is a perspective view looking toward the right side of the tank, and Fig. 4, is a sectional view on the line 4—4, Fig. 1.

I claim:

The ornamental design for a flush tank, substantially as shown.

ANDREW COCHRAN.
